UNITED STATES PATENT OFFICE.

ABRAM N. ACKERMAN, OF PASSAIC, NEW JERSEY.

WINDING-SHELL FOR CALICO, &c.

SPECIFICATION forming part of Letters Patent No. 267,817, dated November 21, 1882.

Application filed April 11, 1882. (No model.)

To all whom it may concern:

Be it known that I, ABRAM N. ACKERMAN, of Passaic, in the county of Passaic and State of New Jersey, have invented a new and Improved Winding-Shell for Calico, &c., of which the following is a specification.

My invention relates to the hollow wooden shells which are used for winding long strips of calico, cotton cloth, or other fabric or paper, or similar material into large rolls; and it consists of a metal casting consisting of a central portion which has a square passage through it and a surrounding ring or ferrule connected to the central portion by fins, the casting to be forced into the ends of the shell for strengthening the same and for furnishing a metal socket, bushing, or clutch for connecting the ordinary power-shank for revolving the shell.

Reference is to be had to the accompanying drawings, forming part of this specification, in which similar letters of reference indicate corresponding parts in both the figures.

Figure 1 is a central sectional elevation of an ordinary wooden winding-shell having my metal bushing and ferrule applied thereto; and Fig. 2 is an end elevation of the same.

A represents the wooden winding-shell, which is of the ordinary form and construction; and B B represent the castings or bushings applied to the ends thereof. The central portion, a, of the casting or bushing is by preference deeper than the surrounding ring b, and is of an external size equal to or a little greater than the bore of the shell A, and has the square central passage, f, through it, as shown clearly in Fig. 2. The surrounding ring b, which forms the ferrule part of the casting, is joined to the central portion, a, by the radial fins c c, which are by preference made slightly tapering from their outer to their inner edges. The ring b is also made slightly tapering from its outer to its inner edge, as shown in Fig. 1, to facilitate the driving or forcing of the casting into the ends of the shell. The castings will be forced by suitable power into the ends of the winding-shell before the shell is put into the lathe to be turned up, and suitably attached to the lathe-dogs for turning, so that

when the shell is turned the castings will always be properly centered.

In use the ordinary square shank used for communicating power to the ordinary shells will be inserted into the square passages f, and the power applied in the ordinary manner. It will be seen that the central portion, a, of the casting thus furnishes a metal bushing for the ends of the shell, which protects the shell and furnishes a clutch for the square shank. The ring b, when the castings are forced into the shell, incloses and to a considerable extent compresses the portions d d of the material of the shell between the ring and the central portion, a, of the casting, and acts as a ferrule to those portions, thus adding greatly to the strength and durability of the shell.

In order to strengthen the fins c c and to facilitate the removal of the pattern in the casting of the device, I prefer to re-enforce the fins at the corner where they join the ring b and central portion, a, as shown at i i in Fig. 2.

Having thus fully described my invention, I claim as new and desire to secure by Letters Patent—

1. As a new article of manufacture, a combined bushing and ferrule for winding-shells, consisting of the central portion, a, having a square hole, f, the tapering rim b, and the tapering fins c, connecting the rim and central portion together, the said central portion being deeper than the rim, substantially as herein shown and described.

2. The combination, with the shell A, of the casting B, consisting of the apertured central portion, a, the tapering rim C, and the tapering fins c, connecting the central portion and rim together, substantially as herein shown and described, whereby the casting serves the double purpose of a bushing for the shell and means for securing it in a lathe for turning up said shell, as set forth.

ABRAM N. ACKERMAN.
